UNITED STATES PATENT OFFICE.

LOUIS R. KELLEY, OF BETHLEHEM, PENNSYLVANIA, ASSIGNOR TO BETHLEHEM FOUNDRY & MACHINE COMPANY, A CORPORATION OF PENNSYLVANIA.

FEEDING AND LUTING DEVICE FOR METALLURGICAL FURNACES.

Application filed November 11, 1924. Serial No. 749,122.

To all whom it may concern:

Be it known that I, LOUIS R. KELLEY, a citizen of the United States, residing at Bethlehem, in the county of Northampton and State of Pennsylvania, have invented certain new and useful Improvements in Feeding and Luting Devices for Metallurgical Furnaces, of which the following is a specification.

10 The object is to provide in ore roasting and other metallurgical furnaces, composed of a plurality of superimposed hearths surrounding a rotating shaft, means to feed the ore or other material from a drying platform, or from one hearth, to a hearth platform, or from one hearth, to a hearth therebelow, which means however insures the rate with which ore is fed from one hearth to a second hearth therebelow.

Another object is to provide in this connection the combination of a hearth having an enlarged central opening, with a shaft extending through and in spaced relation with the sides of said opening, a groove formed by the shape or arrangement of 25 the inner rings of fire-brick composing the hearth, or by an annular channelled metal plate secured to said hearth, and a so-called feed-plate carried by said shaft and provided with a depending cylindrical flange 30 extending into the ore in said groove.

This plate flange is provided at one point with a notch, and with a gate, comprising a plane body portion pivotally carried by the plate and having an angularly depending portion forming a scraper, the bottom edge of which is just high enough above the plane of the top surface of the fire-bricks to provide clearance. With this construction, a further object therefore is to 40 provide a feeding device which cannot disturb the ore in the lute-groove as it feeds new ore constantly over said groove and towards the central opening in the hearth.

Still another object which follows as a 45 natural sequence is to provide a trap or gas-tight joint between the hearth and the shaft, the first ore in the groove filling the same about and in close contact with both sides of the plate flange and thus 50 preventing gases from a lower hearth passing upwardly through the central aperture and into an upper hearth chamber, except at the notch in the flange, which however

is constantly choked full with incoming ore as it is impelled by the scraper through 55 said notch.

And a still further object is to provide adjustable means, extending into the interior of the rotatable shaft which is hollow, and pivotally connected with the gate whereby altering said adjustable means varies the rate with which ore is fed from one hearth to a second hearth therebelow.

With these and other objects in view, the present invention comprises additional 65 novel details of construction and operation hereinafter fully brought out in the following description when read in conjunction with the accompanying drawings, in which Fig. 1 is a vertical diametrical section through a portion of a metallurgical furnace of the type hereinbefore referred to; Fig. 2 is a fragmentary section on the line 2—2 of Fig. 1; and Fig. 3 is a side 70 elevation of the plate lute-apron and feed- 75 ing gate shown in Figs. 1 and 2.

Referring to the drawings, a furnace is shown as comprising cylindrical side walls 1, within which is located a vertical series 80 of superimposed hearths 2 and 3, the hearths 2 having central openings 4 which comparatively closely surround the fire-brick covering 5 of a vertically extending centrally positioned rotatable shaft 6. The hearths 3, on the other hand, are provided 85 with comparatively large central apertures 7, through which ore is adapted to pass from said last-named hearths to the hearths therebeneath, ore from the first-named hearths 2 passing to the hearths 3 by way of suitably positioned openings 8 adjacent to the surrounding wall 1.

Assuming that ore has been dried upon a platform above that portion shown in the drawing and has fallen by gravity through the uppermost aperture 7, it is deflected by an angularly disposed flange 9 carried by the shaft 6, so that none of it will pass through the aperture 4, but instead flow radially along the surface of the hearth 2, said ore being carried outwardly partly by gravity and partly by suitable rabbles carried by rabbles-arms (neither of which is illustrated), which in turn are supported by the rotatable shaft.

The ore having reached the outer periph-

ery of this hearth passes through the one or more openings 8 therein and falls upon the hearth 3, whence it is made to progress radially, or rather spirally, towards the center of this second hearth by means of suitably supported rabbles as above referred to. The first ore to approach the central portion of the hearth 3 falls into and fills the channel 10, comprising a so-called lute-groove formed by a series of sectional channel members secured together in any suitable manner, as for instance by means of radially extending abutting flanges 11 (shown in Fig. 2).

15 Carried by the shaft 6 is a feedplate 12, also formed of segmental members secured together by radially extending flanges 13, secured in any suitable manner (as also shown in Fig. 2). Said segmental members 20 therefore lying in a common plane and together comprising the plate 12 are provided with depending segmental flanges, which being in annular alignment form a continuous cylindrical flange 14, which depends 25 from said plate so that its lower end extends well into the lute-groove 10 and considerably below the level or the plane of the upper surface of the fire-brick of the surrounding hearth. While the shaft revolves and carries with it the feed-plate and depending flange, it will be obvious that there is a constant gas-tight connection formed by the ore in the lute-groove in conjunction with said flange to prevent gases 30 from the lower hearth passing upwardly through the opening 7 and into an upper hearth chamber. So much for the luting feature of this improved construction.

The flange 14 is provided at one point 40 with a notch 15, adjacent to which is a lug 16, suitably drilled and adapted to receive a pinion-pin 17 which also extends through a lug or boss 18 upon the gate member. This gate member comprises a horizontally extending plane body portion 19, slidable upon the upper surface of the plate 12. An angularly positioned, downwardly extending scraper portion 20 is adapted to extend radially outwardly beyond the circular path 45 14, and impel ore with which it comes into contact inwardly through the notch 15, the lower edge of the scraper being so positioned as to afford ample clearance with respect to the adjacent surface of the hearth.

50 In order to adjust the angular position of the scraper 20 and thereby regulate the rate with which the ore from the hearth 3 is fed toward the opening 7, a rod 21 is pivotally connected at 22 to the gate and extends into the interior of the shaft 6, where a suitable hand-wheel or the like 23 is provided for adjustably positioning said rod radially. Having effected the desired adjustment of the feed-gate, the continued motion of the 55 shaft will cause the scraper as it engages

the ore to maintain said gate in the outermost position permitted by the adjustment of the rod.

However, if it is desired to remove this tension from the rod, the gate member may 70 be fixed in any desired position by any suitable means such for instance as the bolts which removably secure an upwardly extending flange 24 carried by the gate with a similarly positioned segmental flange 25 75 carried by that plate-segment 12 which is provided with a notch 15.

This construction accordingly provides an efficient feeding device in conjunction with the luting device hereinbefore described, and 80 of such a construction that gases, prevented from rising past the feed-plate, will likewise be prevented from passing through the notch 15, due to the constant filling or choking of said notch with ore passing there-through under the impelling influence of the gate scraper 20.

Having thus described my invention, what I claim and desire to protect by Letters Patent of the United States is:—

1. In a furnace, the combination of a hearth having an annular groove, a cylindrical member having a lower edge portion revolvable in said groove and having a notch, and a pivotally mounted gate carried by said member, said gate comprising an upwardly extending scraper portion normally positioned angularly with respect to said member and operative to impel ore through 95 said notch, and comprising a substantially extending portion integral with said first portion and operative to prevent ore encountered by said scraper portion from piling against and falling back over said scraper portion.

2. In a furnace, the combination of a hearth having an annular groove, a cylindrical member having a lower edge portion revolvable in said groove and having a notch, a pivotally mounted gate carried by said member, said gate comprising an upwardly extending scraper portion normally positioned angularly with respect to said member and operative to impel ore through said notch, and comprising a substantially extending portion integral with said first portion and operative to prevent ore encountered by said scraper portion from piling against and falling back over said scraper 110 portion, a hollow shaft to carry said cylindrical member, a rod pivotally connected with said gate and extending into the interior of said shaft, and means to maintain said rod in adjustable normally fixed positions 115 to maintain the desired angular position of the scraper portion of said gate.

3. In a furnace, the combination of a hearth having a central opening, a circumferentially positioned series of channelled 130

members together providing an annular groove adjacent to said opening, a rotatable shaft, a plate carried by said shaft and having a depending cylindrical flange extending 5 into said groove.

4. In a furnace, the combination of a hearth having a central opening, a circumferentially positioned series of channelled members together providing an annular groove adjacent to said opening, a rotatable shaft, a plate carried by said shaft and having a depending cylindrical flange extending into said groove, a notch in said flange, and a scraper pivotally carried by 10 said plate and operative upon the rotation of said shaft to impel ore from said hearth through said notch and towards said opening.

5. In a furnace, the combination of a hearth having a central opening, a circumferentially positioned series of channelled members together providing an annular groove adjacent to said opening, a rotatable shaft, a plate carried by said shaft and having a depending cylindrical flange extending into said groove, a notch in said flange, and a gate pivotally carried by said plate and comprising a scraper operative upon the rotation of said shaft to impel ore from said hearth through said notch and towards said opening, and a disc-like body portion spanning the distance between the scraper and the plate to prevent ore from escaping and falling back over the scraper.

35 6. In a metallurgical furnace, the combi-

nation of a central shaft, a hearth having a central opening through which ore may drop to a hearth below, and provided with an annular channel iron providing an annular groove adjacent to said opening, a structure comprising a plate secured to said shaft above the level of said hearth and a depending flange carried by said plate and extending into said annular groove and having an opening above the level of the hearth, 45 and a scraper pivotally carried by said structure and adapted to feed ore through the opening in said flange.

7. In a metallurgical furnace, the combination of a central shaft, a hearth having a central opening through which ore may drop to a hearth below, and provided with an annular channel iron providing an annular groove adjacent to said opening, a structure comprising a plate secured to said shaft above the level of said hearth and a depending flange carried by said plate and extending into said annular groove and having an opening above the level of the hearth, 50 and a gate having a plane body portion pivotally carried by and in slidable engagement with said plate and having a depending angularly extending portion comprising a scraper, operative to feed ore through the opening in said flange towards the opening 55 in the hearth.

In testimony whereof I have affixed my signature.

LOUIS R. KELLEY.
